UNITED STATES PATENT OFFICE

159,533

BAR TOOL

John Przybyla, Chicago, Ill.

Application May 24, 1949, Serial No. 2,849

Term of patent 7 years

(Cl. D44—29)

To all whom it may concern:

Be it known that I, John Przybyla, a citizen of the United States, residing at 8543 South Marquette Avenue, Chicago, in the county of Cook and State of Illinois, have invented a new, original, and ornamental Design for a Bar Tool, of which the following is a specification, reference being had to the accompanying drawing, forming part thereof.

Figure 1 is a top view of a bar tool showing my new design;

Figure 2 is a side view thereof;

Figure 3 is a bottom view thereof; and

Figure 4 is an isometric view thereof.

I claim:

The ornamental design for a bar tool, as shown.

JOHN PRZYBYLA.
